UNITED STATES PATENT OFFICE.

LAURA E. SILLS, OF ST. PAUL, MINNESOTA.

LAMP-SHADE.

1,189,746.

Specification of Letters Patent. Patented July 4, 1916.

Application filed November 23, 1914. Serial No. 873,503.

To all whom it may concern:

Be it known that I, LAURA E. SILLS, a citizen of the United States, residing at St. Paul, in the county of Ramsey and State of Minnesota, have invented a new and useful Improvement in Lamp-Shades, of which the following is a specification.

The primary object of my invention is to provide an improved adjustable shade for 10 artificial lights, such as are employed on vehicles, whereby a portion of the concentrated rays are cut off, so that light may be shaded from the eyes of persons approaching when either on foot or riding without 15 obscuring the road ahead. Thus my invention overcomes the hazard of blinding persons in approaching automobile caused by the glare of light.

Further objects of the invention are simplicity and inexpensive construction.

To these ends my invention comprises the features of construction and combination of parts hereinafter more particularly described and set forth in the claims.

25 In the drawing, Figure 1 is a side elevation, partly broken away of an automobile lamp, showing my improved shade applied thereto, and in longitudinal section; Fig. 2 is a plan of the construction illustrated in 30 Fig. 1, a portion of the shade being broken away and shown in section taken upon the line X—X, of Fig. 1.

For convenience in illustrating my invention, the same is shown applied in use 35 to an automobile head light, although its use is applicable to other kinds of lamps.

A indicates a lamp of usual design having the usual lens carrying door 2 on its front portion, supported by a hinge 3 and 40 held closer by a fastener of any kind, such as the spring catch 4, said lens being adapted to close the usual light projection opening 1.

My invention has two main parts, a shield B, and a shade, vizor or hood C, said shield 45 being telescopically connected with said shade adjustably. The shield B consists of a thin plate of metal or other suitable material fastened around the surface of the top portion of the door 2, by soldering, brazing, 50 or other suitable means. Said plate is formed with a concave portion 5 around its edge adjacent the door, which conforms with the shape of the surface of the door, to which the shield is fastened. The lower 55 ends of the shield are of greater width than the intermediate portion, the shield

being formed with downwardly and forwardly inclined projections 6 producing ends of sufficient width to permit the shade swinging up or down and allowing any 60 light to radiate upwardly from the lamp. The shade C is in the form of a vizor extending forwardly with its lower edge 7 adjustable in height, so that the amount of light radiating forwardly and laterally 65 from the lamp can be controlled by the user. The upper rearward end of the shade is secured to the intermediate or concave portion 5 of the shield by a hinge 8, which permits the shade to be swung upwardly and 70 downwardly. For the purpose of holding the shade in adjusted position in elevation, a slot 9 and thumb nut and bolt 10 are associated with the ends of the shield and the shade, the slot being formed in one 75 member and the bolt passing through said slot and secured to the opposite member.

The construction illustrated shows the slot in each end portion of the shield and the bolt 10 passing through said slot and secured to the adjacent portion of the shade. Each slot 9 extends in a curve described from a hinge 5 as a center, leaving the shade 80 free to swing and be adjusted by loosening the bolt 10, and to be secured in adjusted position by retightening the bolt. It is obvious that the shield can be constructed as an integral part of the lamp and that the shade can be hinged to the lamp proper instead of to the shield, these variations in 85 construction being the equivalent of the precise form illustrated in the drawing. The door 2, which carries the shield and shade can be swung open or closed upon the hinge 3 and when closed is adapted to be held by 90 the spring fastener 4, which engages over a 95 projecting shoulder 11 on the door.

The invention in use enables the operator to adjust the shade in elevation by tilting it so that the light of the lamp on an automobile or other vehicle may be cut off to an effective line or elevation, without reducing the intensity of the light, and so that it will avoid the hazard of blinding a person approaching on foot or riding.

In accordance with the patent statutes, I have described the principles of operation of my invention together with the apparatus which I now consider to represent the best embodiment thereof, but I desire to have it 100 understood that the construction shown is only illustrative, and that the invention can 110

be carried out by other means and applied to uses other than those above set forth within the scope of the following claims.

Having described my invention, what I claim as new and desire to protect by Letters Patent is:—

1. The combination with a head light having a body provided with a light projection opening, a shade hingedly supported at its upper end by said body and projecting forwardly therefrom, the lower portion of said shade telescoping upon said body, and means extending through the telescoping portions of said body and shade for adjustably securing such portions together.

2. In combination with a head light having a door thereon formed with a light projection opening, a shield mounted upon said door and extending around the upper portion of said opening, said shield projecting forwardly from said door, a shade hingedly supported from the upper portion of said door having its lower side portions telescopically connected with the lower ends of said shield and means for adjustably securing said shade upon said shield when said shade is swung up or down.

3. The combination with a head light

having a body, of a shade hingedly supported at its upper end by said body to project forwardly therefrom and having its lower portion telescoping upon said body, the telescoping portions of said body and said shade being provided with registering slots, and means working within said slots for adjustably securing the telescoping portions of said body and shade together.

4. The combination with a head light having a body, of a shade hingedly supported at its upper end by said body to project forwardly therefrom and having its lower portion telescoping upon said body, the telescoping portions of said body and said shade being provided with registering elongated arcuate slots, and means working within said slots for adjustably securing the telescoping portions of said body and shade together.

In testimony whereof, I have signed my name to this specification, in the presence of two subscribing witnesses.

LAURA E. SILLS.
